(57) **CLAIM**

I claim the ornamental design for a snuffer tool, as shown and described.

DESCRIPTION

FIG. 1 is a perspective view of a snuffer tool showing my new design;

FIG. 2 is a front elevational view thereof; the rear elevational view, left-side elevational view, and right-side elevational view all being identical thereto;

FIG. 3 is a top plan view thereof;

FIG. 4 is a bottom plan view thereof; and,

FIG. 5 is a cross-sectional view of FIG. 3, taken along lines 5-5.
